US00D617323S

(12) **United States Design Patent**
Willenz

(10) **Patent No.:** **US D617,323 S**
(45) **Date of Patent:** **** Jun. 8, 2010**

(54) **MEMORY DEVICE**

(75) Inventor: **Sylvain Willenz**, Brussels (BE)

(73) Assignee: **Freecom B.V.**, Rijswijk (NL)

(**) Term: **14 Years**

(21) Appl. No.: **29/329,491**

(22) Filed: **Dec. 16, 2008**

(51) LOC (9) Cl. **14-02**

(52) U.S. Cl. **D14/356**

(58) **Field of Classification Search** **D14/137, D14/167, 168, 230, 231, 233, 235, 237, 240–242, D14/299, 432, 435, 436, 155, 496, 300, 301, D14/313, 314, 214, 348–363, 365–370; D18/56; D13/149, 162, 184, 199; D3/201, D3/273; D27/186, 189; D9/420, 423; 312/223.1, 312/223.2; 369/34.01, 36.01, 272.1; 360/132, 360/133, 135; 361/679.31–679.45**

See application file for complete search history.

(57) **CLAIM**

The ornamental design for a memory device, as shown and described.

DESCRIPTION

FIG. 1 is a perspective view of a memory device; FIG. 2 is a top plan view of the memory device of FIG. 1; FIG. 3 is a bottom plan view of the memory device of FIG. 1; FIG. 4 is a front elevational view of the memory device of FIG. 1; FIG. 5 is a rear elevational view of the memory device of FIG. 1; FIG. 6 is a left side elevational view of the memory device of FIG. 1; FIG. 7 is a right side elevational view of the memory device of FIG. 1; and, FIG. 8 is a rear elevational view of the memory device of FIG. 1 with a cover in an open position.

Features illustrated with dashed lines are not considered features of the invention being claimed, but rather illustrate an exemplary environment for the claimed features illustrated with solid lines.
